FINGER RING

Lee Hirsch, New York, N. Y.

Application December 5, 1931. Serial No. 579,163

7 Claims. (Cl. 63—15)

This invention relates to finger rings and particularly to rings of the type commonly worn with other rings. It enables a person to wear a pair of rings, such as a wedding ring and an engagement ring, for example, in such relation to each other as to display both rings to best advantage with no discomfort to the wearer.

It is well known that when a wedding ring and an engagement ring are worn upon the same finger, as is the common custom, the setting of the engagement ring tends to conflict with the upper portion of the wedding ring. This may result in one or more of various undesirable effects. For example the setting of the engagement ring 5 may extend over a portion of the wedding ring with the result that the latter is largely concealed and the two rings become interlocked in an objectionable way. On the other hand if the wedding ring cannot take a position beneath the 10 setting of the engagement ring, the latter will have a tendency to assume an angular position on the finger. The inner band of the engagement ring will assume a position adjacent the band of the wedding ring while the setting at the top 15 of the engagement ring will hold the two rings further apart on the exposed part of the finger. This not only results in a display of the engagement ring setting at a disadvantage, but also places the setting well out upon the finger and 20 has a tendency to create an uncomfortable feeling. In accordance with the present invention, the wedding ring is so modified that it will not force the engagement ring setting forwardly 25 on the finger and in turn will not be concealed by the engagement ring. The construction is such 30 that the two rings may assume their natural positions with their central axes in line with the axis of the finger and the engagement ring may at the same time assume a position well up on 35 the finger.

A further feature of the present invention is in the formation of the parts so that the ring will be held against turning upon the finger. This 45 feature coupled with the fact that the ring will in no part be concealed by the engagement ring renders the invention particularly applicable to a 50 wedding ring set with stones or otherwise ornamented across the upper portion of its periphery. Other features and advantages of the invention 55 will appear from a detailed description of an 60 illustrative form of the same which will now be given in conjunction with the accompanying drawing, in which:

Fig. 1 is a perspective view of a ring embody-

ing the invention, as seen largely from one face, and

Fig. 2 is a side view of the ring showing its relation to the finger and to another ring, indicated in broken lines.

Referring now to the drawing, it will be observed that the illustrative ring comprises an upper portion 10, a bottom portion 11 and intermediate connecting portions 12. The upper portion 10 may be of any suitable form, either flat 65 across the top to any desired extent, or provided with irregular surfaces, or a series of flat sides, or made truly arcuate. It may vary suitably be provided with ornamental configurations or it may carry a series of stones 13, or it may simply 70 be left plain. These are all matters of design which may be very readily embodied, more or less as a matter of choice, in a ring employing the features of the invention. The lower portion 11 of the ring is preferably semi-circular in form so 75 as to adapt it to follow the contour of the under surface of the finger. This portion will normally be left plain, although it will be apparent that if desired it may also be either set with stones or ornamentally configured. The relation between 80 the portions 10 and 11 is preferably such that they fall in separate planes, each of which is perpendicular to the axis of the finger as the ring is worn. Certain of the advantages of the invention may be derived, however, if the two portions 85 are left in the same plane but joined by an offset portion, or if the planes of the two portions are arranged at a slight angle to each other in lieu of being strictly parallel.

The connecting portions 12 between the upper 90 and lower parts are preferably simply inclined at an angle of, say, 45° to the planes of the main portions, although they may, if desired, be inclined at any other suitable angle or simply be in the form of a reverse or S curve of small radius.

As the ring is applied to the finger, it will be placed with the lower portion 11 well against the webs 14 on either side of the finger. This portion of the ring thus falls naturally into a small pocket or recess formed in the finger at its point of junction with the palm of the hand. The portions 12 then overlie the webs 14 at the two sides of the finger, while the top portion 10 assumes a position substantially perpendicular to the axis of the finger but in a plane somewhat closer to the main knuckle. This top part of the ring then rests further back upon the finger than would be possible, at least without tilting of the ring as a whole, if all parts of the ring were in a single plane. Since an inclined or offset portion 12 105 110

overlies each of the webs 14 at the two sides of the finger, it will be apparent that turning of the ring upon the finger will be more or less effectively prevented. This is distinctly advantageous where 5 the ring is provided with stones or ornamentation on only a portion of its periphery since it insures proper display of this portion at all times.

As made apparent in Figure 2, the set-back relation of the top portion of the ring with respect 10 to the lower portion permits another ring 15, such as an engagement ring shown in broken lines, to assume its natural position without interference with the wedding ring. The lower portion of ring 15 may be in close proximity to the lower portion 15 11 of the other ring without causing any angling of the ring 15 to accommodate its setting 16. This not only improves the appearance presented by the two rings but also creates a more comfortable feeling due to maintaining the engagement ring 20 setting further removed from the finger joint.

It is to be noted that while the ring as viewed alone presents an appearance quite different from that of the ordinary ring, particularly as viewed from the side, this difference is not apparent as 25 the ring is worn. When the ring is worn, its side portions are concealed by the adjacent fingers. It should be observed, furthermore, that the various advantages pointed out are obtained without the necessity of removing any of the metal of the 30 ring. This is an important consideration in the modern type of ring, which is usually a relatively thin band.

While the invention has been disclosed as particularly applicable to a wedding ring, it will be 35 apparent that it is also applicable to any type of finger ring which is intended to be worn in conjunction with other rings having overhanging settings. It may also be applied to advantage to any form of ring which it is desirable to retain in 40 a definite position on the finger. Furthermore, it should be understood that while the inclined portions 12 are shown at substantially the mid-points of the sides of the ring, they may be located at somewhat higher or lower points, although 45 it is considered preferable to so position them that they will fall just above the webs between the fingers. Various other changes in the form and relation of the different portions of the ring may be made without departing from the 50 general principles and scope of the invention as defined by the claims.

I claim:

1. A wedding ring comprising a single, rigid,

continuous band having its major upper and lower portions in different substantially parallel planes approximately at right angles to the axis of the ring, said upper and lower portions being connected by angled portions at the sides of the 80 ring.

2. A wedding ring having two portions extending substantially across the finger aperture offset with relation to each other and rigidly joined by integral, angled portions to completely 85 encircle the finger, said offset portions being arranged in separate substantially parallel planes substantially at right angles to the axis of the ring.

3. A wedding ring comprising a single, rigid 90 band having angular shoulders provided at opposite sides on one face of the ring adapted to engage the webs at the opposite sides of the finger to prevent rotation of the ring.

4. A wedding ring comprising a single, rigid 95 band having upper and lower portions offset and connected by web engaging portions providing a pair of shoulders on one face at the sides of the ring.

5. A wedding ring comprising a single, rigid 100 band having its major upper and lower portions offset into different, substantially parallel planes at approximately right angles to the axis of the ring, connecting portions joining said upper and lower portions and providing a pair of abrupt 105 shoulders on one face adapted to engage the webs at the two sides of a finger, the arrangement being such as to lock the ring on the finger and prevent rotation thereof, and to accommodate the setting of an adjacent ring without conceal- 110 ment of the wedding ring.

6. A wedding ring comprising a single, rigid, continuous band having its major upper portion substantially in a plane, and its major lower portion substantially in another plane, each of said 115 planes being arranged at not less than an angle of 75° to the axis of the ring.

7. A wedding ring comprising a single, continuous, rigid band having an upper portion and a lower portion, each extending substantially 120 across the finger aperture and each lying substantially in a plane, the planes of the two portions being different and intersecting the axis of the ring at an angle of not less than 75°, and integral portions at the sides of the ring joining 125 said upper and lower portions.
